UNITED STATES PATENT OFFICE.

CARL E. WENZEL, OF NEWARK, NEW JERSEY.

DETONATING TOY.

SPECIFICATION forming part of Letters Patent No. 764,023, dated July 5, 1904.

Application filed October 8, 1903. Serial No. 176,190. (No model.)

To all whom it may concern:

Be it known that I, CARL E. WENZEL, a citizen of the United States, residing at Newark, in the county of Essex and State of New Jersey, have invented and produced new and original Improvements in Detonating Toys; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

15 The objects of this invention are to provide a detonating toy in the form of a donkey or similar animal, to secure for this purpose suitable detonating apparatus, to thus provide a novel and pleasing toy, and to obtain other advantages and results, some of which may be hereinafter referred to in connection with the description of the working parts.

The invention consists in the improved detonating toy and in the arrangements and combinations of parts of the same, all substantially as will be hereinafter set forth, and finally embraced in the clauses of the claim.

Referring to the accompanying drawings, in which like numerals of reference indicate corresponding parts in each of the several figures, Figure 1 is an elevation of my improved detonating toy with a portion of the side wall broken away to disclose the interior mechanism. Figs. 2 and 3 are vertical cross-sections on lines *x* and *y*, respectively, of Fig. 1 looking in the directions indicated by arrows and the hammer being removed in the latter. Fig. 4 is a detail view of the hammer looking at its striking-face; and Fig. 5 is a section on the broken line *z z*, showing the cap-strip-feeding means.

In said drawings, 1 indicates the body portion of my improved device, having the form of a donkey or other animal, providing front legs 2 3, a neck 4, and head 5, with nostrils or outlets 6. The whole is cast or otherwise formed out of metal in sections which are fastened together in any suitable manner, as by screws 7, to form a hollow chamber.

50 In the head 5 is an anvil 8, preferably cast

integral with one of the sections of the body portion and having perforations 9 to provide as free an access as possible for smoke from an explosion on said anvil downwardly forward through the said head 5. Coinciding 55 with the nostrils are openings 10 to vent the said smoke and give an appearance of the animal sneezing at every explosion. To engage said anvil 8, a hammer 11 is arranged to extend backwardly downward through the neck 60 4, being pivoted, as at 12, above the fore legs 2 3 and adapted to swing transversely of the said neck 4 in a vertical plane. Between the shank of said hammer and the wall of the neck 4 of the body portion is arranged a cap-strip-65 feed guide 13, comprising a flattened tube slotted longitudinally at its side next the hammer. Said cap-feed extends from an entrance-slit 14 in the body portion 1 to the said anvil 8, which latter has contiguous to the end of 70 said feed-guide a transverse groove 15, adapted to receive a rib 16 on the hammer 11, and which serves to sever each cap as it is exploded.

Above the hammer 11 and near its rear end 75 or end pivoted upon the stud 12 is a T-shaped lever 17, pivoted at the junction of its arms upon another transverse stud 18. The long arm 19 of said lever projects forwardly past the hammer 11 at one side thereof into close 80 proximity to the slotted cap-guide 13 and carries pivoted to its end a feed-dog 20, the free end of which is pressed into the slot 21 of the guide 13 by a spring 22, projecting from the stud 18. Of the opposite short arms of the 85 lever 17 one, as 23, projects forwardly upward and is connected by a link 24 to the hammer-shank, while the other, 25, projects rearwardly downward and affords attachment for a spiral spring 26, secured at its other end 90 to a stud 27 on the body. Thus it will be understood that the hammer 11 is normally held against the anvil 8, with the feed-dog 20 at a lower point of the cap-guide 13, and that when said hammer is raised or retracted for a stroke 95 the long arm 19 of the T-shaped lever is swung upwardly forward, carrying the feed-dog with it, and thus sliding the cap-strip along to project a cap upon the anvil 8, which the hammer has just left. Spurs 33, fixed at the 100

lower end of the guide 13, positively prevent any backward dragging of the cap - strip. For retracting the hammer 11 I employ one of the fore legs 2 as a trigger, the same being pivoted, as at 28, and provided at its upper end with an interior lug or projection 29. A spring 30 normally holds the trigger or fore leg 2 in normal position, and the hammer is preferably provided with a pawl 31, pivoted 10 on its lower end and projecting downward behind the same or at the rear of its fulcrum, which thereby forms a stop. A spring 32 normally holds said pawl forward against said stop, and its lower end is adapted to be engaged by the said projection 29 on the trigger, so that as the projection moves forward it carries the pawl with it until they pass out of reach of each other, and when the projection moves rearward the pawl yields to allow 20 it passage. Any other suitable and well-known connection of the hammer and leg 2 could obviously be employed, if desired.

Having thus described the invention, what I claim as new is—

- 25 1. In a detonating toy, the combination with a hollow body portion in the form of an animal having a head with open muzzle, a neck and a pivoted leg, of an anvil in the head of said body portion, means for feeding caps to said anvil, a hammer extending down through the neck, and tripping means for said hammer adapted to be engaged by the said pivoted leg.
- 30 2. In a detonating toy, the combination with a hollow body portion having the form of an animal and providing a head with open nostrils, a neck and a pivoted leg, of an anvil in said head, ducts for the passage of smoke from said anvil to the said open nostrils of the head, means for feeding caps onto said anvil, a hammer extending through said neck and tripping means for said hammer adapted to be engaged by said pivoted leg.
- 35 3. In a detonating toy, the combination with a hollow body portion in the form of an animal and having a head with open nostrils, a neck and a pivoted fore leg, of an anvil in said head of the body portion, said anvil being perforated to permit the smoke of an explosion to pass to said nostrils, means for feeding caps to said anvil, a hammer arranged in the said neck, and tripping means adapted to engage the said hammer and be engaged by the said fore leg.
- 40 4. In a detonating toy, the combination with

a fixed cap-strip guideway having a longitudinal slot, of a pivoted hammer lying at the slotted side of the said guideway and in substantially the same plane therewith, a bent lever pivoted at the opposite side of said hammer from the cap-guide upon a pin parallel to the pivot of said hammer, one arm extending past said hammer to a point adjacent to the cap-guide, a spring-pawl on said last-mentioned arm, projecting into the slot of the guide, and means connecting said lever to the hammer.

5. In a detonating toy, the combination with a fixed cap-strip guideway having at one side a longitudinal slot, a pivoted hammer adapted to swing in a plane passing through said cap-guide, a bent lever pivoted at the opposite side of said hammer from the cap-guide upon an axis parallel to that of said hammer and having one arm extending past one side of said hammer to a point adjacent to the said slot of the cap-guide and means connecting said lever to the hammer.

6. In a detonating toy, the combination with a fixed cap-strip guideway having at one side a longitudinal slot, a pivoted hammer adapted to swing in the plane of said slot, a bent lever pivoted upon an axis parallel to that of the hammer and having an arm extending into proximity to the said slot of the cap-guide, a spring-pawl on said last-mentioned arm, projecting into the slot of the guide, and a rigid link connecting the other arm of said lever to the hammer.

7. In a detonating toy, the combination with a fixed cap-strip guideway having at one side a longitudinal slot, a pivoted hammer lying alongside said cap-guide, a T-shaped lever pivoted on the opposite side of said hammer from the cap-guide and having its long arm extending past the same, a spring-pawl upon said long arm, projecting into the slot of the guideway, a link connecting one of the short arms of the T-lever to the hammer, and a spiral spring attached to the other short arm, substantially as set forth.

In testimony that I claim the foregoing I have hereunto set my hand this 23d day of September, 1903.

CARL E. WENZEL.
